UNITED STATES PATENT OFFICE.

WALTER J. BARRON, FRANZ X. WAGNER, AND AMOS DENSMORE, OF NEW YORK, N. Y.; SAID BARRON AND WAGNER ASSIGNORS TO SAID DENSMORE.

TYPE-WRITING MACHINE.

SPECIFICATION forming part of Letters Patent No. 484,132, dated October 11, 1892.

Application filed October 28, 1889. Serial No. 328,371. (No model.)

To all whom it may concern:

Be it known that we, WALTER J. BARRON, FRANZ X. WAGNER, and AMOS DENSMORE, citizens of the United States, residing at New York city, in the county of New York, State of New York, have invented certain new and useful Improvements in Type-Writing Machines, of which the following is a specification, reference being had therein to the accompanying drawings.

Our invention relates to type-writing machines in which a separate finger-key and type-lever are used to impress each letter or character; and the objects of our invention are, first, to propel the paper-carriage with the spring which operates the universal bar; second, to operate the letter-space movement with a push-pawl acting upon a rack having its teeth inclined in one direction and arrest it by a pawl acting upon a rack having its teeth inclined in the opposite direction, the retaining-pawl being connected with the universal bar, and also to provide a follower-dog to prevent the carriage from moving when a key is struck and also lock said carriage when it is taken from the machine and unlock it as it is let down or replaced; third, to provide the frame and carriage with means to render the latter removable, and thereby prevent tampering therewith; fourth, to provide means for operating the universal bar located above the finger-key levers or at a point above the bottom of said levers; fifth, to provide the machine with a square platen independent of the feed-rolls.

Other means for retaining the key-levers and the keys in position will be hereinafter described in connection with the drawings, in which—

Figure 1 is a top view of a type-writing machine constructed in accordance with our invention with the carriage-guiding frame partly broken away. Fig. 2 is a longitudinal vertical section of the same. Fig. 3 is a rear view of the frame of the machine, showing the carriage advancing and retaining mechanism. Fig. 4 is a side view of the line-space-operating and paper-feeding-in mechanism. Fig. 5 is a vertical section of the paper-carriage, taken from the opposite end of that shown in Fig.

2, with the hand-levers and other parts in position to facilitate the introduction of the paper or to permit the printing to be examined. Fig. 6 is a perspective view of the finger-key and of one of the key-levers. Fig. 7 is a side view of the rear end of one of the key-levers, with modified means to connect it with the universal bar, shown in section. Fig. 8 is a top view of the rear end of a few key-levers, showing the means to retain them in position and united to the frame of the machine. Fig. 9 is a top view of a rod and connections to operate the propelling and the retaining pawl of the paper-carriage. Fig. 10 is a side view of the bearing-plate for the line-space lever. Fig. 11 is a side view of a line-space lever. Fig. 12 is a side view of the locking-lever. Fig. 13 is one end plate of the paper-carriage frame with the ribbon-moving plate alongside. Fig. 14 is a transverse section of the paper-table. Fig. 15 is a transverse section of the paper-directing plate. Fig. 16 is a front view of the ribbon-propelling mechanism. Fig. 17 is a perspective view of one of the type-levers, its bearing and operating lever and connecting-rod. Fig. 18 is a plan of the carriage with the paper-feeding rollers, the ribbon-spools, and the bearings for the latter removed from said carriage. Fig. 19 is a transverse sectional elevation of the same.

In said drawings, A represents the base-frame of the machine, A² the sides, and A³ the top frame, all rigidly united together, the frame A³ consisting of a downwardly-flanged ring having four arms A⁴, by which it is secured to the sides A². Upon the frame A³ are secured the bearings B of the type-levers b, said levers being pivoted thereto at b². Each lever b is operated by means of a bell-crank lever b³, pivoted to the bearing B at b⁴. The opposite end of the lever b³ is provided with a loop b⁵, having a rectangular eye, through which the lever b passes loosely. The angular portion of the bell-crank lever b³ has a pin b⁶, to which is pivoted the upper section c of a connecting-rod to operate the type-lever. The lower section c² of said connecting-rod is pivoted at c³ to a strap c⁴, attached to the key-lever C. To render the connecting-

rod longitudinally adjustable, the lower end of the section c and the upper end of the section c^2 are provided with transverse serrations c^5 , adapted to interlock together, and they are 5 clamped together by a longitudinally-split spring-sleeve c^6 , in form of a C in cross-section. Each bearing B has its outer end secured to the top frame A^3 by means of a screw B^2 . The outer half of said bearing is in the form of an 10 inverted trough, (U) to the sides of which the pivots b^2 and b^4 are secured. The upper end of the section c of the connecting-rod is flattened, so as to lay alongside of the bell-crank lever within said trough of the bearing B when the 15 type-lever is at rest. The inner half of said bearing is a continuation of the bottom only of the trough and extends toward the center of the top frame A^3 more than half of the length of its radius, and at its inner end its sides are 20 flanged down to provide an inverted-V-shaped groove b^7 to receive a wedge-shaped projection b^8 upon the type-lever about half-way of its length and guide the type at the inner end thereof in the proper place to make an impression. The key-levers have their rear 25 ends pivoted to a cylindrical rod A^5 , which extends from one side of the frame to the other. Each lever has a semicircular notch in its upper edge to receive the under side of 30 the rod A^5 , and to retain said parts in engagement and the finger-keys elevated spring-wires C^2 are used. Said wires are preferably bent double in the middle of their lengths, and the looped end thus produced is 35 inserted under a bracket A^6 , projecting inwardly from the rear of the machine, and adjustably retained by screws passing through its end and through the sides A^2 of the frame. The portions of the wire adjacent 40 to the looped end are made to bear upon the rod A^5 , and the ends are made to engage under small hooked portions C^8 , projecting from the side of the body of the key-lever. To prevent the rod A^5 from sagging, it is sustained in the middle of its length and at other 45 points by screws A^7 , passing through lugs projecting inwardly from the rear bar of the frame A. Each key-lever is provided at its front end with a flattened tubular key-holder 50 C^4 , secured thereto, and within the upper end of said holder is inserted the flat stem C^5 of the finger-key C^6 . To guide and retain the key-holders in a vertical position, they are made to pass through vertically-slotted bridges A^8 , 55 that may be either solid or in the form of hollow parallelograms or in the form of a trough and that extend from one of the sides A^2 to the other and have their ends secured to the frame. The key-levers are retained apart in 60 proper position between their two ends by bent wires C^8 , that straddle and frictionally clamp every alternate key-lever.

To produce the letter-space movement or advance of the carriage D toward the left-hand side of the machine, said carriage is provided with two racks D^2 and D^3 in the rear thereof. Said racks are rigidly attached to-

gether at a short distance apart by screws and parting-pieces D^4 . They are carried by arms D^5 , pivoted to the ends of the carriage by 70 screws at D^6 , and the right-hand arm D^5 extends forward beyond said carriage and terminates in a handle D^7 , upon which the operator can press to raise the racks from engagement with their pawls when he desires to slide the carriage to the right or left. Otherwisesaid racks are retained normally in engagement with said pawls by the spring D^8 , having one end secured to the carriage and the other end pressing upon the rack-bars. The racks D^2 80 D^3 have their teeth beveled in opposite directions. The teeth of the inner rack D^2 receive the end of the push-pawl d and of the spring-dog d^2 , and the teeth of the outer rack D^3 receive the upper end of the flat spring-rod d^3 , 85 which prevents the carriage moving more than one space. When a finger-key is struck, the rod d^3 drops out of engagement with one tooth. It then returns and engages the next tooth by means hereinafter described and is carried 90 forward by the rack until stopped by the set-screw d^4 , Fig. 3, projecting laterally from a post d^5 , standing upon a plate A^9 , secured to the top of the frame A^3 by means of the screws 2.

The push-pawl d is retracted for engagement with a new tooth by pressing upon any one of the finger-keys, said pressure being transmitted by the universal rod E, that is suspended by means of links E^6 from the crank-arms E^2 , Figs. 3 and 9, inwardly projecting 100 from the ends of a rod E^3 , which is pivoted to the sides A^2 of the frame. This rod E^3 has also a crank-arm E^4 in the center of its length. Said crank-arm also extends inwardly of the machine and is longer than the crank-arms 105 E^2 and has secured to its free end an arm E^5 , to which the lower end of the rack-retaining rod d^3 is pivoted. The universal rod E is located at a point higher than the bottom of the key-levers C to facilitate its connection with the spring-pawl d^3 , and it is shown at a point even higher than the top in Figs. 1, 2, and 3, 110 and said key-levers are connected therewith by means of hooks e , having their lower ends pivoted to said key-lever and their hooked 115 upper ends resting upon the universal bar. In the modification shown in Fig. 7 the hook e^2 is made integral with the key-lever and the universal bar E is introduced undersaid hook through a groove e^3 , alongside thereof, and the connecting-rods E^6 , that unite the universal bar to the crank-arms E^2 and E^4 , is longer 120 than in Figs. 2 and 3. In Fig. 3 only a few hooks e have been shown, so as to simplify the figure. The push-pawl d is pivoted to the upper ends of an arm d^6 , which has at its lower end a horizontal arm d^7 , forming therewith a bell-crank that is pivoted by means of a screw d^8 to the lower end of a bracket A^{10} , secured to the under side of the ring-frame A^3 . To 125 pull downwardly the free end of the arm d^7 every time a finger-key is pressed down, the rod E^3 has also a crank-arm E^7 , extending a short distance inwardly of the machine, to

the inner end of which is screwed a short cylindrical rod E⁸, parallel with the rod E⁹, and said rod E⁸ is united to the arm d⁷ by means of a connecting-rod E⁹, having an eye on its lower end, that receives the rod E⁸, and a screw at its upper end, that enters a horizontal slot in the arm d⁷, and as the location of said screw and rod E⁹ can be adjusted relatively to the pivot d⁸ of the bell-crank the length of the oscillation of the push-pawl d can be regulated. The free end of said pawl is retained in contact with the teeth of the rack D² by means of a light spring d', pressing against the under side of said pawl.

15 To press the push-pawl d forward and advance the paper-carriage, the main spring A¹² is used to press laterally against the pawl-carrying arm d⁶. Said spring is flat and has its upper end bent to one side at right angles 20 to its body and passed through a rectangular perforation in the bracket A⁹ and is fastened thereto with a screw. Said spring also operates to hold the rod E⁸ normally elevated.

To prevent the paper-carriage from moving 25 farther than desired under the impulse of the push-pawl and main spring when a key is released after being struck, the friction-dog d² has its beveled point made to bear against the teeth of the rack D². Said dog is pivoted to a 30 plate f², secured to the rearside of the guide-rail F, upon which the rear wheels of the carriage run. A light spring f³, attached to the heel of the dog d², retains the bevel-point in contact with the rack. A second function of the 35 dog d² is to lock the carriage to the guide-rail when said carriage is raised or removed from the machine. For this purpose a bell-crank-shaped dog f⁴ is pivoted, also, to the plate f² and has its upper end shouldered to engage 40 under the free end of the dog d² under the impulse of the spring f³, that unites it to the heel of the dog d².

In Fig. 3 the parts are shown in normal position for use, with the lower end f⁵ of lever 45 f⁴ resting upon the bracket A⁹ and its shouldered upper end thrown out of engagement with the under side of the dog d²; but when the carriage and its supporting-frame, carrying the plate f², are elevated (see Fig. 2) the 50 lower end of the lever f⁴ is raised out of contact with the plate A⁹, and the shouldered upper end thereof is thus permitted to engage and lock the dog d² in contact with the rack. By this construction the carriage is 55 automatically locked as soon as it is lifted by raising the frame, consisting of the guide-rails F F' and end straps F², and it is unlocked as soon as it is replaced in position for use and the print-line can be continued from where 60 it was left off.

The carriage-supporting frame consists of two end straps F², united at a suitable distance apart by the rear guide-rail F and the front guide-rail F' for the carriage. The 65 straps F² rest on top of the sides A² of the frame. The rear ends of the straps F² are bent slightly upward and rearward and are

provided with substantially-cylindrical ends to constitute a journal F³, that is received in the bent end of an arm A¹³, extending rearwardly from the two sides A² of the frame, and to prevent any lateral displacement of the carriage-supporting frame and permit it to be tilted rearwardly even beyond a vertical position the arms A¹³ have vertical slots 70 to receive pins F⁴, projecting rearwardly from the journals F³ through said slotted bearings, so that the front of the carriage can be elevated and made to occupy a position much to the rear of that shown by dotted lines in Fig. 80 2, or it can be lifted entirely off its bearings.

The feed-roll K has its journal k retained in bearings d', formed in the end plate of the carriage D. Upon one end of said journal the ratchet-wheel k² is secured, and in engagement with the periphery of said wheel is the upper pawl g and also the lower pawl g² of the line-space lever G, the two pawls being 85 also connected together by the coil-spring g³.

The lever G is mounted on a pivot-screw g⁴, 90 that is secured to a plate g⁵, and said plate has one end pivoted at 3, Fig. 10, upon the journal k of the feed-roll, while the opposite end rests upon the front longitudinal bar of the paper-carriage D, and it is normally kept 95 down upon said bar by means of the connecting-rod h of the latch-lever H, said connecting-rod having about the middle of its length a laterally-extending-pin h², that is normally latched or retained in a notch in the rear side 100 of the standard D⁶, projecting upward from the end plate of the paper-carriage. The forward end of the rod h is slotted and straddles a pin or screw g⁶. The rear end of this rod is also slotted and receives the upper end of the 105 lever H, to which it is connected by means of a pin h³. Said upper end of lever H is in the form of a hook h⁴, so as to bear upon a triangular pin g⁷, projecting laterally from the upper pawl g of the line-space lever and which locks said pawl or its triangular pin in 110 engagement with the ratchet-wheel k² when the front end of the lever H is lifted or pinched against the under side of the lever G to release the rod h, and consequently the plate g⁵, 115 to permit the then connected levers G H to be elevated to the position shown in Fig. 5 and the feed-rolls to be thus rotated.

The roll K² is rotated by frictional contact with the roll K or with the paper between them. To cause said friction, the bearings K³ of said roller K² are pivoted at 4 to the end plates of the carriage and have shoulders on their front edges, against which press the outer ends of flat springs K⁴, secured to the 120 front bar of the paper-carriage, said springs being adjusted thereto by means of screws K⁵, Fig. 1.

The platen I consists of a square rod covered with rubber or other suitable material 130 and can be turned by hand to present either side to the types. It is held in bearings formed in the end plates of the paper-carriage, and is retained in proper position and

prevented from rotating by a spring I^3 , secured to one of the end plates and pressing against one of the sides of the square head of said platen. Above the platen and loosely in 5 enclosing three of its sides there is a curved plate L to direct the paper under and beyond said platen, said plate L being stationary and secured to the end plates of the paper-carriage by lugs L^2 and screws inserted therein 10 and in the holes l^2 of the end plates. In front of the front edge of the movable paper-table J there is a narrow segmental plate L^3 to direct the paper toward the feed-rolls. The paper-table J is pivoted at j , Fig. 14, to the 15 end arms L^4 of the plate L and is pressed away from in front of the platen, when the parts are in normal position to print, by an arm g^8 , extending down from the plate g^5 and pressing against a lug j^2 on one end of the 20 paper-table; but when the levers G H are turned up, as shown in Fig. 5, the paper-table is released from engagement by the arm g^8 and is advanced under the platen by its spring J^2 . The carriage is not intended to be raised 25 when it is desired to see the writing; but the paper P is intended to be rolled forward and upward to the front side of roll K when the line-space lever G and the latch-lever H under it are pinched and raised. When these 30 levers are lowered to normal position, the paper will return to printing-point. When the levers G H are in their normal position, Figs. 2 and 4, the platen I is exposed; but when they are raised the platen I is, as shown in 35 Fig. 5, by the movable paper-table J to facilitate the introduction of the paper into the machine. The levers must be slightly raised when the paper is inserted in the machine. This permits the paper to be slid in from the 40 rear past the platen, as the movable paper-table J drops forward until its front end is beyond the under side of the said platen, the downward motion of the paper-table being aided by the spiral spring J^2 , that has one end 45 secured to the side frame J^3 of said paper-table and the other to the carriage. After the paper has reached the rear of the feed-rolls K and K^2 it is advanced between and beyond them by elevating the levers G H still higher, 50 or substantially as shown in Fig. 5, and pulling the paper by hand a half an inch or more to insure its being clamped by the feed-rolls when the levers are returned to their normal positions. 55 To retain the ribbon R elevated nearly in contact with the platen or with the paper upon which the printing is to be done, a thin and narrow strip of sheet metal n extends fore and aft of the machine under said platen, 60 alongside of the printing-point. The front end of said strip n is secured to the front guide-rail F' and carries a pointer n^2 , Figs. 1 and 2, that extends upward either upon or under the scale N , carried by the carriage, and indicates 65 upon said scale the position of the last letter printed. The ends of the scale N are secured to the front rail of the carriage by means of

straps N^2 , that extend in front of the feed-roll K and help to sustain the front end of the paper upward, while the middle wire finger N^3 extends still higher. 70

The ribbon R is carried upon spools R' and R^2 , mounted on brackets R^3 , attached at diagonal corners of the paper-carriage. To automatically wind the ribbon the distance of 75 one notch of the ratchet-wheel R^4 , mounted upon the axle of the spool R^2 , every time the hand-lever G is lifted to advance the paper one line, a pawl r is made to engage with the ratchet-wheel R^4 by means of a spring r^2 , pressing 80 against a radial lug on its hub. The pawl r is pivoted on one end of a lever r^3 , that is pivoted about the middle of its length at r^4 to the bracket R^3 . The opposite end of the lever r^3 is kept normally elevated by a small 85 spring r^5 , and is thus pressed against the under side of the plate R^5 , Figs. 4 and 13, which has a cut-away or beveled portion r^6 , into which cut-away recess the end of the lever r^3 enters under the impulse of its spring r^5 when 90 the plate R^5 is moved rearward toward the operator, and thus causes the pawl r to engage under a new tooth of the ratchet-wheel R^4 ; but when the plate R^5 is released and permitted to move 95 forward under the impulse of the spring s , attached to its rear, its beveled portion r^6 rides over the spring-suspended end of the lever r^3 and elevates its opposite end, carrying the pawl r , and thus revolves the ribbon-spools a short distance. 100

The plate R^5 is moved forward toward the operator by a pin r^7 , projecting from the side of the pendent arm of the lever G , pressing against a lug R^6 , projecting upward from the 105 upper edge of the plate R^5 , every time the lever G is lifted and rocked upon its bearing to advance the paper-feed roll one line. 110

Having now fully described our invention, we claim—

1. In a type-writing machine, the combination of key-levers and straps thereon with type-levers and connecting-rods uniting them to the straps of the key-levers, said connecting-rods consisting of two sections having serrations on their adjacent ends and a sleeve embracing and uniting said serrated ends of the sections, substantially as described. 115

2. The combination of key-levers and type-levers with trough-shaped bearings B for said type-levers, bell-crank levers b^3 , pivoted, also, to said bearings and provided with a loop b^5 , and connecting-rods having their upper ends pivoted to the bell-crank and flattened to enter between the sides of the trough-shaped 120 bearings alongside of the bell-crank, substantially as described. 125

3. The combination of the frame of a type-writing machine, the rod A^5 , secured thereto, the bracket A^6 , and key-levers having hooked portions C^3 with the wires C^2 under the bracket and hooked portions and resting upon the rod A^5 , substantially as described. 130

4. The combination of the frame of a type-

writing machine, the guide-bridges A⁸, having one edge vertically slotted for the reception of the key-levers, the key-levers, the flattened tubular key-holder C⁵, and finger-keys, each 5 having a flat stem inserted in said holder, substantially as described.

5. The combination of the frame of a type-writing machine and its type-bar bearings, the plate A⁹ above said bearings and secured 10 to said frame, the bracket A¹⁰ under said plate, and the pawl-carrying arm d⁶, pivoted to the bracket, with a spring A¹², pressing against said arm d⁶, a pawl upon said arm, and the rack of the paper-carriage engaging with said 15 pawl, substantially as described.

6. The combination of a paper-carriage frame, two racks having their teeth in the same horizontal plane and inclined in opposite directions and rigidly secured together, 20 but hinged to said carriage-frame, a push-pawl d, in engagement with one of the racks, and a retaining pawl or rod d⁸, in engagement with the other rack, and the universal rod E, connected to said rod d⁸, substantially as described. 25

7. The combination of a paper-carriage frame, two racks having their teeth in the same horizontal plane and inclined in opposite directions and rigidly secured together, 30 but hinged to said carriage-frame, and having a handle D⁷, extending in front of said carriage, and a pawl in engagement with each rack, substantially as described.

8. The combination of a paper-carriage frame, two racks having their teeth inclined in opposite directions and rigidly secured together, but hinged to said carriage-frame, and a pawl in engagement with each rack with the universal bar of a type-writing machine 40 and means, substantially as described, for connecting the universal bar with the pawls operating the paper-carriage, substantially as described.

9. The combination of a paper-carriage frame, two racks having their teeth inclined in opposite directions and rigidly secured together, pawls d and d⁸, in engagement with said racks, and the dog d², also in engagement with one of the racks, substantially as described. 50

10. The combination of the type-bars and their bearings, the plate A⁹ above said bearings, the paper-carriage and its guide-rail F, and the rack D² and its pawl d with the dog d² 55 and the bell-crank-shaped dog f⁴, substantially as and for the purpose described.

11. The combination of the frame of a type-writing machine and its rearwardly-extended arms A¹³, having bearings at the rear ends 60 thereof and slots in said bearings, with the carriage-supporting frame having end straps F², rearwardly projecting and provided with journals F³ and pins F⁴ radially extending therefrom, substantially as described.

65 12. The combination of the paper-carriage frame, its revoluble square platen and retain-

ing-spring I², and two paper-feed rolls having their point of contact on a level above said platen, substantially as described.

13. The combination of the paper-carriage frame, its revoluble polygonal platen and retaining-spring I², two feed-rolls having their point of contact on a level above said platen, and a ratchet-wheel upon the end of one of the feed-rolls with a line-space lever G and its 75 pawl in engagement with said ratchet-wheel, substantially as described.

14. The combination of the paper-carriage frame, its revoluble polygonal platen and retaining-spring I², a feed-roll above said platen, 80 a ratchet-wheel upon said feed-roll, and a plate g⁵, pivoted upon the journal of the feed-roll, with a line-space lever pivoted upon said plate g⁵ and its pawl in engagement with the ratchet of the feed-roll, substantially as described. 85

15. The combination of the paper-carriage frame, its polygonal platen, a feed-roll above said platen, a ratchet-wheel upon said feed-roll, and a plate g⁵, pivoted upon the journal 90 of the feed-roll, with a line-space lever pivoted upon said plate g⁵ and its pawl in engagement with the ratchet of the feed-roll, a triangular pin g⁷, projecting laterally from the pawl, and the lever H, having a hooked end 95 adapted to rest upon the pin g⁷, substantially as described.

16. The combination of a paper-carriage frame, a paper-feed roll, a ratchet upon said roll, and a plate g⁵, pivoted upon the journal 100 of said roll, with a line-space lever upon said plate g⁵ and its pawl in engagement with the ratchet of the feed-roll, a pin g⁷, projecting laterally from the pawl, and the lever H, having a hooked end adapted to rest upon the 105 pin g⁷, substantially as described.

17. The combination of the paper-carriage frame having at one end the standard D⁹, rearwardly notched, a paper-feed roll, a ratchet-wheel upon said roll, and a plate g⁵, pivoted 110 upon its journal, with a line-space lever pivoted upon said plate, a lever H, pivoted upon the journal of the feed-roll, and the rod h, having one end pivoted to the lever H and the other end loosely retained by the plate g⁵, 115 and a pin h² between said two ends, in engagement with the notch of the frame-standard D⁹, substantially as described.

18. The combination of the paper-carriage frame, its polygonal platen, a feed-roll above 120 said platen, and a paper-directing plate in front and over the platen, substantially as and for the purpose described.

19. The combination of the paper-carriage frame, its polygonal platen, a feed-roll above 125 said platen, the paper-table J, movable under the platen and having its side frames J³ mounted upon the journal of the feed-roll, and the spring J², connecting it with the paper-carriage frame, substantially as described. 130

20. The combination of the paper-carriage, its polygonal platen, a feed-roll above said

platen, the paper-table J, movable under the platen, and plate g^5 , pivoted upon the journal of the paper-feed roll and having an arm g^8 , adapted to press against the edge of the paper-table to normally uncover the platen, substantially as described.

21. The combination of the paper-carriage frame, its polygonal platen, and a feed-roll above said platen with the pressure-roll K^2 , its bearings K^3 , and springs K^4 , carrying said bearings, said springs being secured to the paper-carriage frame, substantially as described.

22. The combination of the paper-carriage frame, its polygonal platen, a feed-roll K above said platen, a pressure-roll K^2 in front of said platen, an inking-ribbon and a metal strip n under said platen, a number-scale, and a

pointer projecting up from said strip, substantially as described.

23. The combination of the paper-carriage frame, its feed-roll, and a polygonal platen under said feed-roll, a metal strip n , an inking-ribbon passing diagonally under said platen and feed-roll, a ratchet-wheel upon the journal of one of the ribbon-spools, the lever r^3 , the pawl r , and plate R^5 , having a beveled end r^6 , substantially as described.

In testimony whereof we affix our signatures in presence of two witnesses.

WALTER J. BARRON.
FRANZ X. WAGNER.
AMOS DENSMORE.

Witnesses:

J. VAN SANTVOORD,
E. F. KASTENHUBER.
